MINIATURE SCREW DRIVER

Harris S. Hart, 3009 McFaddin, Beaumont, Tex. 77702

Filed July 15, 1971, Ser. No. 163,138

Term of patent 14 years

Int. Cl. D8—05

U.S. Cl. D8—85

FIG. 1 is a plan view of a miniature screw driver embodying my design;

FIG. 2 is an end elevation view thereof, taken from the left of FIG. 1;

FIG. 3 is a side elevation view thereof, taken from the right of FIG. 2; and

FIG. 4 is an end elevation view taken from the end opposite FIG. 2.

I claim:

The ornamental design for a miniature screw driver, as shown and described.
